TUYERES PROVIDED WITH COOLANT PASSAGES

Isaac Eugene Cox, Kirkwood, Mo., assignor to American Brake Shoe Company, New York, N. Y., a corporation of Delaware

Continuation of application Serial No. 456,659, September 17, 1954. This application September 20, 1955, Serial No. 535,345

3 Claims. (Cl. 266—41)

This invention relates to tuyeres and methods for making the same.

In the production of steel, as for example in Bessemer and other types of furnaces, the transmission of the required blast of air or other gaseous media through the walls of the furnace requires the provision of elongated nozzle-like tuyeres that are cooled continuously by a constantly replenished flow of liquid coolant such as water. Such tuyeres have presented many problems insofar as manufacture may be concerned and also as to efficiency of operation and flexibility in design and construction. It is therefore the primary object of the present invention to enable tuyeres of the aforesaid character to be manufactured readily and easily and with a high degree of uniformity so as to thereby insure proper and satisfactory operation thereof, and related objects are to enable tuyeres to be produced from a plurality of relatively simple and inexpensive parts, to simplify the form and relationship of the parts of tuyeres of the aforesaid character, and to simplify the assembly of the parts.

Other and important objects of the present invention are to afford a tuyere that has a minimum thermal capacity with the resulting reduction in the weight and cost thereof, to afford a tuyere arrangement in which turbulence of coolant flowing at relatively high velocity is assured so as to break up any tendency for the coolant to vaporize during its passage through the tuyere, and to afford a tuyere that has a large return or discharge area for the coolant as such coolant flows at high velocity along its return path from the inner or hot end of the tuyere.

Other and further objects of the present invention will be apparent from the following description and claims and are illustrated in the accompanying drawings which, by way of illustration, show a preferred embodiment of the present invention and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claims.

In the drawings:

Fig. 1 is a side elevational view of a tuyere and embodying the features of the invention;

Fig. 2 is a longitudinal sectional view of the tuyere at a somewhat enlarged scale;

Fig. 3 is a transverse cross sectional view of the inlet manifolds taken substantially along the line 3—3 of Fig. 2; and

Fig. 4 is a transverse section of the tuyere adjacent the inner or hot end thereof, the view being taken substantially along the line 4—4 of Fig. 2.

For purposes of disclosure, the invention is herein illustrated as embodied in an elongated tuyere 20 that has an outer or cool end 20C and an inner or hot end 20H, and adjacent the outer or cool end 20C, the tuyere 20 has

2

an enlarged manifold structure 21 with which inlet and outlet supply pipes 22 and 23 may be associated to provide for flow of coolant at high velocity such as water through the body of the tuyere 20 as will be described.

5 The tuyere 20 is generally cylindrical in cross section and affords a large area central passage P through its entire length so that the blast of air or other gas may be fed therethrough from the cool end 20C for discharge longitudinally from the hot end 20H of the tuyere. Under and in accordance with the present invention, the tuyere 20 is formed from a plurality of individual structural elements, each of which may be made by conventional metal forming processes to relatively close limits of tolerance so that in subsequent assembly operations, 10 these individual elements or parts of the tuyere may be readily and easily fixed together in a predetermined relationship such that inlet and return coolant passages are afforded within the tuyere from the manifold structure 21 to the forward or hot end 20H of the tuyere and then back 15 to the manifold structure 21.

In affording such a convenient, efficient and economical tuyere structure, especially for high velocity coolant use is made of extruded and cast parts which may be thereafter assembled in a convenient sequence and secured together as by metal fusion or welding to provide a rigid and accurately assembled tuyere. Thus, an inner tuyere tube 25 is afforded of a material such as copper shaped by extrusion, and this inner tube 25 is of substantially the length that is desired in the completed tuyere 20. The primary outer member of the tuyere 20 is afforded by an outer or shroud tube 26 that is also formed in the present instance as an extrusion from a metal such as copper, and this shroud tube 26 is of a length somewhat less than the inner tuyere tube 25, this 20 difference in length being sufficient to provide for mounting of the manifold structure 21 adjacent the outer or cold end 20C of the tuyere tube 25, as will be evident in Fig. 2 of the drawings. At their inner or hot ends, the tubes 25 and 26 are connected by an annular nose cap 27 that may be formed advantageously as a casting made from copper, and these elements are secured together in the manner and sequence that will be hereinafter described.

The manifold structure 21 is afforded by a plurality of 25 case members that are individually formed and machined as required, and thereafter assembled on and with respect to the tubes 25 and 26. Thus the manifold is afforded in part by a circular tube-plate 28 and an inlet manifold casting 29 and an outlet manifold casting 30 which are 30 associated with the other elements to afford the desired inlet and outlet manifolds. The tube plate 28 is utilized not only to afford a division wall between the inlet and outlet manifolds, but also as mounting means for what may be termed the outer ends of a plurality of inlet tubes 35 31 that are disposed in uniformly spaced relationship about the tuyere tube 25 so as to extend longitudinally thereof and provide for passage of coolant from the inlet manifold longitudinally at high velocity along the tuyere structure to a location adjacent to the inner surfaces of the nose cap 27, such coolant then returning to the discharge manifold through the annular return passage 32 that is afforded in the space between the tubes 25 and 26 as will be evident in Fig. 4 of the drawings.

As will be evident particularly in Fig. 2 of the drawings, the inlet manifold casting 29 is generally cup-shaped in form to afford an end wall 29W and an annular side wall 29S. The end wall 29W has a central opening 29B therein which is complementary to the outside surface of the inner tuyere tube 25 so that the opening 29B has a snug fit on the tube 25. The edge of the side wall 29S is formed with an internal rabbeted groove 29G as will be evident in Fig. 2 so that the groove 29G

may fit over the adjacent annular outer edge of the tube plate 28 as will be described in further detail hereinafter. In this relationship, the casting 29 and the plate 28 cooperate with the tube 25 to define an annular inlet or supply manifold 21S. The manifold casting 29 has a nipple 29N formed on the wall 29S through which a threaded inlet opening 29T is provided to receive pipe fittings involved in the connection of the inlet line 22 thereto.

The outlet manifold casting 30 is also generally cup-shaped in form so as to provide a wall 30W and a side wall 30S. The wall 29W has a central opening 30B that is of the same diameter as the internal diameter of the shroud tube 26 and about this opening 30B, an annular rabbeted groove 130G is afforded into which the adjacent end of the shroud tube 26 may extend. The inner edge of the side wall 30S also has a rabbeted groove 30G which may fit over the adjacent outer annular edge of the tube plate 28 as will be described. The plate 28 and the casting 30 thus cooperate to afford an annular return manifold 21R, and a nipple 30N with a threaded opening 30T.

The tube plate 28 is relatively heavy and has a central opening 28B that is complementary to the outer diameter of the tuyere tube 25, thus to afford a snug fit between the tube 25 and the opening 28B. At its outer annular edge, the tube plate 28 has what amounts to a central flange 28F that is so proportioned with respect to the thickness of the plate 28 and the depth of the grooves 29G and 30G that the ends of the wall 29S and 30S will fit against the opposite faces of the flange 28F when the faces or bottoms of the grooves 29G and 30G are engaged with the side faces of the tube plate 28.

The tube plate 28 has a plurality of openings 33 formed in an annular series thereabout and of such a diameter that the ends of the inlet tubes 31 may be extended through the openings 33 as shown in Fig. 2 of the drawings. The dimensioning is such as to afford a relatively snug fit of each tube 31 in its opening 33, and it will be noted that these openings 33 are spaced radially outwardly from the opening 28B. The total area of the inlet tubes 31 is preferably such as to be somewhat less than the net effective area of the annular return passage 32, thus to assure optimum flow conditions for the coolant.

Because of the outward spacing of the openings 33 as above described, the tubes 31 are formed with angular bends 31B therein and thus the portions of the tubes that extend into the bores 33 are parallel to the axis of the tuyere tube 25, and the angular or bent portions 31B extend at a gradual angle toward the outer surface of the tube 25 so that at substantially the plane in which the wall 30W is located, the tubes 31 are brought into contact with the outer surface of the tuyere tube 25 and extend along in contact with such outer surface and longitudinally thereof to substantially the inner ends of the tubes 25 and 26.

The nose cap 27 is also formed as a casting, as hereinbefore pointed out, and is generally in the form of a ring having an internal opening 27B that conforms with the internal diameter of the tuyere tube 25, the outer edge surface 27S of the nose cap 25 conforming substantially with the external diameter of the shroud tube 26. The nose plate 27 is formed with an internal annular groove 27G which reduces the effective wall thickness of the nose cap and affords surfaces for directing the high velocity incoming coolant liquid so as to change or reverse its direction, while at the same time assuring adequate flowing contact of such coolant with the internal surfaces of the nose cap. Furthermore, the nose cap is provided with annular flanges 27F and 127F that are arranged to project into an interlocking or positioning contact with the adjacent cylindrical surfaces of the outer and inner tubes 26 and 25.

The desired form in the tube plate 28, the manifold

elements 29 and 30 and the nose cap 27 is primarily accomplished in the process of casting, but the surfaces thereof that require accurate relationship to other elements of the structure may be formed by the usual processes of drilling, turning and the like. After all of the parts have been formed, such parts are assembled in a predetermined sequence and are secured together by welding to afford the completed tuyere 20. Thus as the first step in the assembly operation, the tube plate 28 is put in position on the tuyere tube 25 and on its opposite faces is welded to the tuyere tube 25 by annular welds W-1 and W-2. After the tube plate 28 is in position, the several inlet tubes 31 are put in position by inserting the outer ends thereof into the openings 33 in the tube plate 28 and rotatively adjusting or positioning the individual inlet tubes 31 so that throughout the major portion of their length they are located in contact with the outer surface of the tuyere tube 25. The tubes 31 are then welded in position by a plurality of tack welds W-3 at spaced points along their length, and at their outer ends, the tubes 31 may be welded to the tube plate 28 as at W-4.

The inlet manifold casting 29 is then put in position and is welded to the outer surface of the tuyere tube 25 by an annular weld W-5, while the wall 29S is welded to the flange 28F by an annular weld W-6. The return manifold casting 30 is then put in position on the tube plate 28 and is secured thereto by an annular weld W-7 as will be evident in Fig. 2 of the drawings.

The shroud tube 26 is then put in position with its outer end located within the rabbeted groove 130G, and while the other or inner end of the shroud tube 26 is properly supported in concentric relation to the tuyere tube 25, the shroud tube 26 is secured to the wall 30W by an annular weld W-8.

The nose cap 27 is then put in position with its annular flanges 27F and 127F extending into the space between the inner ends of the tubes 25 and 26, and the nose cap is then fixed in position by an annular weld W-9 between the tuyere tube 25 and the nose cap, and an annular weld W-10 between the nose cap 27 and the inner end of the shroud tube 26.

In the assembly operations as thus described, it will be observed that the welding operations that are required may readily and easily be performed in each instance, the welding locations being disposed so as to be readily accessible in every instance. When the assembly operations have been completed, the elements of the tuyere are, of course, in a rigid and accurately determined relationship and the proper flow of coolant is assured so that the necessary heat dissipation may be accomplished.

The tuyere that is thus afforded under the present invention is of such a character that it has a great flexibility insofar as design considerations may be concerned, and hence the tuyere may be readily and easily produced to meet the operating conditions that are present in the furnace installation where it is to be used. It will also be evident that the present invention affords a tuyere that is simple and economical in its structure and which may be manufactured with such accuracy of relationship of the parts that proper or optimum operating efficiency will be attained.

Thus, while I have illustrated and described the preferred embodiment of my invention, it is to be understood that this is capable of variation and modification, and I therefore do not wish to be limited to the precise details set forth, but desire to avail myself of such changes and alterations as fall within the purview of the following claims.

This application is a continuation of my application Ser. No. 456,659, filed September 17, 1954, now abandoned.

I claim:

1. In a tuyere, inner and outer sleeves disposed in spaced concentric relation affording an elongated annular

chamber and with their inner ends connected together to form a nose, said outer sleeve being shorter than said inner sleeve so as to terminate in an outer end spaced from the outer end of said inner sleeve, means defining an annular inlet manifold surrounding and secured to said inner sleeve in spaced relation to the outer end of said outer sleeve and having a wall spaced from said outer end of said outer sleeve and disposed in a plane normal to said sleeves, a plurality of inlet tubes disposed in said elongated annular chamber and having outer ends extended through and anchored in said wall and arranged in annular series about and in contact with the inner sleeve, said tubes being secured to said inner sleeve and extended longitudinally along said inner sleeve in fixed relation thereto so as to locate the other ends of said inlet tubes adjacent the inner ends of said sleeves and closely adjacent nose, and means connecting the outer end of said outer sleeve to said wall and cooperating therewith to form an annular discharge manifold.

2. In a tuyere, inner and outer sleeves disposed in spaced concentric relation affording an elongated annular chamber and with their inner ends connected together to form a nose, said outer sleeve being shorter than said inner sleeve so as to terminate in an outer end spaced from the outer end of said inner sleeve, a tube plate secured to said inner sleeve in spaced relation to the outer end of said outer sleeve, a plurality of inlet tubes disposed in said elongated annular chamber and having outer ends extended through and anchored in said plate and arranged in annular series about and in contact with the inner sleeve, said tubes being secured to and extended longitudinally along said inner sleeve in fixed relation thereto so as to locate the other ends of said inlet tubes adjacent the inner ends of said sleeves and closely adjacent said nose, means connecting said plate to said inner sleeve

outwardly of said plate and cooperating therewith to form an annular inlet manifold for said tubes, and means connecting the outer end of said outer sleeve to said plate and cooperating therewith to form an annular discharge manifold.

- 5 3. In a tuyere, inner and outer sleeves disposed in spaced concentric nested relation to afford an elongated annular chamber therebetween and to enable fluid to flow through said inner sleeve, means at corresponding inner 10 ends of said sleeves affording a nose that is to be exposed to a combustion area and through which fluid flowing through the inner sleeve may be discharged into the combustion area, an inlet and an outlet means for coolant, the inlet means being in communication with said chamber, and a plurality of coolant conducting tubes having corresponding inner ends thereof communicating with said inlet means and being arranged about and secured to said inner sleeve and extended longitudinally along said chamber and in contact with said inner sleeve to have the 15 other ends thereof disposed adjacent to said nose to be effective to discharge coolant against the rear face of said nose for deflection therefrom into said annular chamber to be returned therethrough to said outlet means.
- 10 20 25
